US0D1021139S

(12) **United States Design Patent** (10) **Patent No.:** **US D1,021,139 S**
(45) **Date of Patent:** **** Apr. 2, 2024**

(54) **DITCH AND CANAL LINER**

(71) Applicant: **American Leak Detection Irrigation, Inc.**, New Haven, CT (US)

(72) Inventor: **Kenneth L. Suazo**, Espanola, NM (US)

(73) Assignee: **AMERICAN LEAK DETECTION IRRIGATION, INC.**, New Haven, CT (US)

(**) Term: **15 Years**

(21) Appl. No.: **29/787,534**

(22) Filed: **Jun. 7, 2021**

(51) **LOC (14) Cl.** **25-02**

(52) **U.S. Cl.**

USPC **D25/35**; D23/267; D25/199

(58) **Field of Classification Search**

USPC D12/191; D23/259, 267, 308; D24/204-205; D25/2, 35, 68-69, D25/119-125, 136, 164, 199

CPC ... E02B 13/00; E02B 5/02; E04H 4/14; E04H 4/141; E04F 19/024; E04F 11/163

(57) **CLAIM**

The ornamental design for a ditch and canal liner, as shown and described.

DESCRIPTION

FIG. 1 is a perspective view of the ditch and canal liner showing my new design;

FIG. 2 is a front view of the ditch and canal liner of FIG. 1; FIG. 3 is a back view of the ditch and canal liner of FIG. 1; FIG. 4 is a left side view of the ditch and canal liner of FIG. 1;

FIG. 5 is a right side view of the ditch and canal liner of FIG. 1;

FIG. 6 is a top view of the ditch and canal liner of FIG. 1; and,

FIG. 7 is a bottom view of the ditch and canal liner of FIG. 1.

1 Claim, 5 Drawing Sheets
